RAIL BOND FOR ELECTRIC RAILWAYS AND METHOD FOR PRODUCING THE SAME.

Application filed June 10, 1924. Serial No. 719,062.

To all whom it may concern:

Be it known that we, ROBERT FORTER, a citizen of the Republic of Switzerland, residing at Zurich, Republic of Switzerland, and HULDREICH ALTORFER, a citizen of the Republic of Switzerland, residing at Ruti, Republic of Switzerland, have invented certain new and useful Improvements in Rail Bonds for Electric Railways and Methods for Producing the Same, of which the following is a specification.

This invention relates to an improved rail bond for electric railways and to a method for the production of the same.

For electrical connection of rail ends in electrically operated railways it is necessary to employ means which ensure dependable and lasting electrical contact besides being of sufficient mechanical strength and solidity. The rail bonds heretofore used suffer from the drawback that they fail to answer fully one or other of these conditions or else they are too expensive to manufacture.

The rail bond subject of this invention fully answers the aforesaid requirements.

According to the invention each end of an electrical conductor is pressed into a socket (or orifice) having a wide portion at the entrance end and formed in a weldable block consisting of a seamless piece of metal of suitable profile, the full cross section of the conductor entering the wide portion of the socket and the residual part of the conductor within the block being pressed flatwise and compacted without being materially broadened whereby to effect a mechanically and electrically durable connection which excludes the formation of electrically insulating separation (oxidation) surfaces between the conductor and the blocks.

In the production of the described rail bond, for the purpose of obtaining the mechanically and electrically durable connection between the electrical conductor and the block, this block is formed of a tubular member having two opposed broad longitudinal ribs. This member is positioned on the conductor and then the central portion only of the tubular member is compressed until it is substantially flush with the plane of the ribs. This forces the material of the block into intimate contact with

the conductor and somewhat flattens the conductor at the place where the pressure is applied. The original cross-sectional 55 shape of the conductor, at the point where it enters the tubular member, remains unaltered because the tubular member itself at this point is not compressed nor altered in its shape. While the conductor is flattened where the pressure is applied there is no material widening of the conductor in a direction at right angles to the direction of pressure.

In a preferred form of the conductor the 65 conductor is bent in such a manner that the axes of the parts entering the contact pieces are parallel to one another and also to the direction of the rails so that the parts entering the contact pieces are practically 70 subjected only to tension or pressure but not to shear or bending effort.

A preferred method of producing rail bonds for electric railways comprising a conductor and contact pieces on the ends thereof consists in lacing on a conductor tubular members each serving for the formation of two contact pieces spacing said members apart a distance corresponding to the length of the rail bonds, subjecting the 80 central part of each member to pressure, and finally halving each member transversely of the direction of the conductor.

By the particular shape of the contact piece the further advantage is obtained, that 85 the wall-thickness of the contact piece, especially in the direction of the width, may be kept very large and thus relatively large dimensions may be given to the contact piece without necessitating a too strong pressure 90 for producing the connection. The contact piece may be welded directly to the rail and a solid connection thereby made between the contact piece and the rail.

The invention is illustrated by way of examples in the accompanying drawings, in which:

Fig. 1 is an elevation of the first example,

Fig. 2 is a plan and

Fig. 3 is a section on the line $x-x$ of Fig. 1.

Fig. 4 shows a contact block before it is submitted to pressure.

Figs. 5, 6 and 7 are respectively an elevation, a plan and an end view of a second example of the rail bond.

Fig. 8 shows a third example of the rail bond.

Figs. 9 and 10 represent the two stages of the method for manufacturing the rail bond.

In the drawings 1 denotes the electric conductor which may be formed, for example, of a rope of copper wire; 2 denotes the contact pieces of which one is connected with each end of the conductor. Each contact piece consists preferably of wrought iron so that it may be welded in manner known ¹⁰ ¹⁵ ²⁰ ²⁵ ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ prising a tubular portion having a central opening in which one end of the conductor is inserted and having diametrically opposite broad longitudinal ribs, the cylindrical walls of said tubular portion being pressed inwardly toward the conductor throughout a portion of their length to flatten a portion of the conductor and the central opening, said longitudinal ribs serving to prevent spreading of the conductor and the central opening in a lateral direction so that the cross-sectional area and also the periphery of the conductor and the opening are reduced whereby the pressed-in material of said tubular walls compacts the conductor and fills all interstices.

2. A method of producing rail bonds for electric railways comprising a conductor and contact pieces pressed on the ends thereof, consisting in lacing on a conductor tubular members each serving for the formation of two contact pieces, spacing said members apart a distance corresponding to the length

of the rail bonds, subjecting the central part of each member to pressure, and finally halving each member transversely of the direction of the conductor.

3. A method of producing rail bonds for electric railways comprising a conductor and contact pieces pressed on the ends thereof, consisting in lacing on a conductor tubular members of iron each serving for the formation of two contact pieces, spacing said members apart a distance corresponding to the length of the rail bonds, subjecting the central part of each member to pressure, halving each member transversely of the direction of the conductor and finally machining the part of the tubular member on one side of each contact piece which is not pressed inwardly in order to present an even bearing surface.

In testimony whereof we have affixed our signatures.
